WITNESS:

Ralph F. Suber
INVENTOR
BY *Victor J. Evans*
ATTORNEY

UNITED STATES PATENT OFFICE.

RALPH F. SUBER, OF NEW ORLEANS, LOUISIANA.

HANDLE.

Application filed June 21, 1922. Serial No. 569,857.

To all whom it may concern:

Be it known that I, RALPH F. SUBER, a citizen of the United States, residing at New Orleans, in the parish of Orleans and State 5 of Louisiana, have invented new and useful Improvements in Handles, of which the following is a specification.

My present invention has reference to telegraphic transmitters.

10 In carrying out my invention it is my purpose to produce a key for telegraphic transmitters that shall be adjustably connected with the key lever; that shall be of a shape whereby the proper contact of the individual 15 keys will not be interfered with; one wherein the keys shall be constructed of black gum root, the softest wood obtainable and embodying the necessary strength for this purpose, and also one wherein an additional cap 20 or handle for one of the keys shall be adjustably associated therewith.

The drawing, which accompanies and forms part of this application, illustrates a satisfactory embodiment of the improvement 25 reduced to practice, and wherein:—

Figure 1 is a plan view of a telegraph transmitter illustrating the application of the invention, the latter as well as a portion of the lever being in section.

30 Figure 2 is a bottom plan view of the key. Figure 3 is a plan view of the finger piece. In Figure 1 of the drawing, I have shown a conventional form of telegraphic transmitters to which my improved sending key 35 is attached. The transmitter is broadly indicated by the numeral 1.

The sending key lever of the transmitter is indicated by the numeral 2. The key lever is pivotally supported in the usual manner 40 and has secured to its outer end my improved key 4. As disclosed by the drawing, the key

4 has its inner and narrower ends notched or slotted, as at 5 to receive therein the straight ends of the levers 2. The securing means 6 for the key adjustably connect the 45 same to the lever so that the key may be moved longitudinally toward or away from the lever to which it is connected. The connecting means is firm so that accidental removal of the key from the lever will be prevented. 50

The key 4 is formed of black gum root which is the softest wood that will answer the constant contacting of the operator's fingers thereagainst without inflicting injury 55 to the wood or without inflicting injury to the fingers of the operator.

On the key 4 there is adjustably secured the finger piece 7. The finger piece is of the usual construction, except that the outer face thereof is rounded downwardly from its center to its peripheral edge. The finger piece may be brought to either of two positions on the key 4, as disclosed by the drawing, and it is thought that the foregoing description, when taken in connection with the drawing will fully set forth the construction and advantages of the improvement to those skilled in the art to which such inventions relate. 70

Having described the invention, I claim:—

A telegraph key having a longitudinally extending groove in one face thereof and extending through one end thereof, a transversely extending perforation through said key at said groove, and said key having other transverse openings therethrough in rear of the groove, said second named openings forming means whereby a finger piece may be secured to the key. 75

In testimony whereof I affix my signature.

RALPH F. SUBER.
